UNITED STATES PATENT OFFICE.

WALTER D. FORBES, OF OAKLAND, CALIFORNIA.

BATHING-SUIT.

1,121,177.

Specification of Letters Patent.

Patented Dec. 15, 1914.

Application filed September 16, 1912. Serial No. 720,487.

To all whom it may concern:

Be it known that I, WALTER D. FORBES, a citizen of the United States, residing at Oakland, in the county of Alameda and 5 State of California, have invented new and useful Improvements in Bathing-Suits, of which the following is a specification.

This invention relates to bathing suits, and in particular to that style of suits 10 known as one-piece suits.

The object of the invention is to construct a close fitting one-piece swimming suit which will not hinder the free movement of the limbs and in which the loose 15 skirt portion which is now usually employed and required, may be entirely removed.

A further object of the invention is generally to improve this class of swimming suits so as to reduce the weight and increase 20 their utility and durability.

The invention further consists in the novel construction and arrangement of the parts, all of which will be hereinafter more particularly set forth in the following drawings, 25 specifications and claims, in which—

Figure 1 is a perspective view showing the application of the swimming suit. Fig. 2 is a cross section of a suit showing supplementary flaps 3 attached to the front and 30 rear of the suit.

The object of this invention is to construct a one-piece swimming suit in which the free movement of the limbs of the swimmer will in no manner be retarded, and in 35 which all excess material as the skirt portion which is usually employed and required, may be removed, while still properly protecting the body. With this object in view, I have constructed a continuous one-piece suit 2, as shown in Fig. 1, in which the skirt portion is entirely removed, but in place of which and with the object in view of accomplishing the same purpose, I have applied a flap or apron portion 3, 40 which may be sewed, or otherwise secured to the suit, as shown. A supplementary attachment of this nature accomplishes the object sought, much more effectively than the skirt portion now usually employed, as 45 the skirt becomes very easily disarranged when certain positions are assumed by the 50

wearer. Displacement of the attachment here shown can not take place under any position, as the attachment is always held in position by being secured along the edges 55 4, 5, and 6; the only free edge being the lower portion of same, which allows this to assume a straight line across this portion of the body. From this it can be seen that the object sought is more thoroughly accomplished than where the skirt is used, and that at the same time a great saving in 60 material has been accomplished by eliminating the skirt. Another advantage gained is the removal of considerable excess weight, 65 which is of great importance where suits of this kind are used in swimming races, and for like purposes, as it not only reduces the weight of the suit, but also lessens the drag or friction when swimming. 70

It is obvious that the flap or apron may be applied to both the front and rear portion of the suit, as shown in Fig. 2, and that various modifications of same may be constructed. 75

Having thus described my invention, what I claim and desire to secure by Letters Patent, is—

1. As an article of manufacture, a one-piece bathing suit forming shirt and trunks, 80 and supplemental front and back apron portions lying in planes which are normally substantially parallel one to the other, the lines of the attachment of the sides of said aprons being substantially diametrically opposed lines on the opposite sides of the front and rear thigh portions of the trunks. 85

2. As an article of manufacture, a one-piece bathing suit comprising a shirt and trunks, and a supplemental apron secured 90 to the outside of the suit, said apron lying wholly in a plane which is normally substantially tangent to the front of the thighs of the wearer.

In testimony whereof I have hereunto set 95 my hand in the presence of two subscribing witnesses.

WALTER D. FORBES.
